UNITED STATES PATENT OFFICE.

EVINA AGHA KEMP, OF NEW YORK, N. Y.

DEVICE FOR DISPLAYING FLOWERS.

Application filed May 14, 1924. Serial No. 713,167.

This invention relates to devices for displaying flowers, and aims to provide a new and attractive means for exposing flowers and foliage to view whereby a novel and pleasing effect is secured and the beauty of the flowers and foliage is displayed to better advantage than when viewed in the usual way.

A device according to the invention comprises a container of transparent material and of rounded shape adapted to be filled with water or other suitable transparent liquid, means for sealing the opening of the container, means for holding the flowers in display position in the liquid within the container, and means for illuminating the flowers.

While it is well known to keep plants, and particularly water plants, for display purposes under water in transparent receptacles, such displays do not produce the results secured by my new method.

A full understanding of the invention can best be given by a detailed description of a device embodying the invention, and the use of the same. Such a device is shown in the accompanying drawings; in which:—

Fig. 1 is a vertical central sectional view of the device taken on line 1—1 of Fig. 2; Fig. 2 is a view thereof on line 2—2 of Fig. 1;

Fig. 3 is a plan view of the base member; and

Fig. 4 a partial vertical section taken on line 4—4 of Fig. 2.

Referring to the drawings, 10 represents a container of transparent material, preferably glass, and of spherical or other rounded shape having a neck 11 provided with an external thread 12 which is adapted to engage the internal thread 13 of an annular recess 14 formed in a base member 15. The base 15 is made of wood, non-rusting metal or other suitable material, and forms a liquid-tight closure for the container when screwed on to the neck 11 thereof. A gasket of rubber or other suitable material at the bottom of the recess 14 forms a seat for the edge of the neck 11 and provides a liquid-tight joint between the edge of the neck and the base 15.

The central portion of the base 15, which is formed to extend upward into the neck of the container, serves as a flower holder, being adapted to hold the stems B of the flowers indicated at A. As shown, this cen-

tral portion is provided with a plurality of holes 17 into which the stems of the flowers are inserted. In order to hold the flowers in place and prevent them from floating freely in the liquid, a covering 18 of sheet rubber or other elastic sheet material is secured over the holes 17 and formed with slits 19 in alignment with holes 17 to permit the flower stems to be inserted therethrough into the holes. Thus a flower stem inserted through a slit 19 into the corresponding hole 17 will be gripped by the elastic covering 18 and firmly held in place. A stand 20 serves to receive the base 15 and support the assembled device as shown in Fig. 1.

It is desirable to provide the device with means for illuminating the flowers and the liquid in the container. For this purpose in the construction shown, the base 15 has a central through opening or chamber 25 to accommodate a small electric light bulb 26 mounted on and supplied with current by a battery 27. The battery 27 is most desirably located in a recess in the bottom of the base 15 and rests on a supporting plate 28 hinged to the underside of the base at 29 and locked in supporting position by means of a latch 30 pivoted to the base 31. The battery and lamp circuit is open between two contacts 32, 32' on the casing of the battery. When desired, the circuit may be closed by means of a switch lever 33 made of conducting material and pivoted at 34 to the bottom of the base 15. In Fig. 2 the switch is shown in the open position, the closed position being indicated in dotted lines. The inner end of the central opening 25 is hermetically sealed by means of a lens 35 mounted in a suitable holder 36.

The stand 20 is of such construction as to readily permit access to the switch lever 33 so that the light may be turned on and off as desired. In the particular construction shown the stand 20 is formed as a cylindrical shell having legs 40 and open at the bottom and provided with an internal circular flange 41 adapted to support the base member 15.

In using the device, the flowers or foliage to be displayed are arranged in the flower holder of base 15, and the globe 10 is filled with water, and the base member 15 with the flowers depending therefrom is then screwed on to the neck 11 of the globe, care being

taken that as little free air as possible is trapped in the globe. A small amount of air from the holes 17 of the flower holder will be trapped in the globe. During this 5 operation the stems of the flowers cannot fall out of the holes 17 as they are tightly held by the covering 18. The device is then inverted and placed in the stand 20.

The flowers or foliage as viewed through 10 the spherical or other convex wall of the container and the water are magnified in size. Air contained within the petals of the flowers and the leaves and stems when the flowers are placed within the water-filled 15 container moves outward to the surface of the flowers and leaves and stems and collects in small globules which adhere thereto and produce a very noticeable and pleasing effect, which is intensified by the illumination 20 of the flowers and surrounding liquid by means of the lamp within the base 15.

A variety of color effects may be produced by employing a suitably colored liquid or colored glass for the globe 10, the lens 35, 25 or the light bulb 26.

What I claim is:

1. A device for displaying flowers and the like, comprising a liquid container having an opening and having a transparent wall, 30 means for sealing said opening, means for holding flowers in display position in liquid within the container, and a source of light adjacent said sealing means, said sealing means being formed to permit the passage of 35 light from said source to illuminate the flowers in the container.

2. A device for displaying flowers and the like, comprising a liquid container having an opening and having a transparent wall, 40 a base member formed to seal said opening and provided with means for holding flowers in display position in liquid within the container, and a source of light adjacent said base member, said base member being 45 formed to permit the passage of light from said source to illuminate flowers in the container.

3. A device for displaying flowers and the like, comprising a liquid container of transparent material having rounded walls and 50 having an opening, a base member formed to seal said opening and provided with means for holding flowers in display position in liquid within the container and having a light-transmitting wall, and an electric 55 light bulb mounted adjacent the light transmitting wall of the base member.

4. A device for displaying flowers and the like, comprising a spherical liquid container of transparent material having an opening, 60 a base formed to serve as a liquid-tight closure for said opening and a flower holder, the flower holder having holes therein to receive the stems of the flowers and having a covering of elastic material secured thereto formed with openings aligned with said holes adapted to grip the flower stems and hold them in place.

5. A device for displaying flowers and the like, comprising a liquid container of transparent material having rounded walls and 70 having an opening, a base formed to serve as a liquid-tight closure for said opening and having its central portion formed to serve as a flower holder and having an opening 75 therein provided with a light-transmitting closure at its inner end, and a source of light within said opening.

6. A device for displaying flowers and the like, comprising a liquid container of transparent material having rounded walls and having an opening, a base formed to serve as a liquid-tight closure for said opening and having its central portion formed to serve as a flower holder and having an opening 80 therein provided with a light-transmitting closure at its inner end, an electric light bulb within said opening, and a battery for supplying current to said light bulb mounted in a recess in the base and provided with a 85 circuit controlling switch.

In testimony whereof I have hereunto set my hand.

EVINA AGHA KEMP.
